UNITED STATES PATENT OFFICE

JOHN S. FORBES, OF OVERBROOK, PENNSYLVANIA

HEATER

Application filed April 12, 1928. Serial No. 269,320.

A principal object of the invention is to provide a heater particularly adapted for installation in bathrooms, physicians' offices and the like for the purpose of heating the same and embodying a movable radiative shelf-like member or plate normally occupying a substantially vertical position but which may be raised therefrom to a substantially horizontal position to thereby provide a convenient support upon which may be disposed and heated or dried if desired, articles such as towels, food and medicine containers and the like.

A further object of the invention is to provide a heater of the general character of that to which reference has been made which is compact, simple in design and construction and thus not liable to get out of order or become damaged under conditions of use; which can be manufactured at a relatively low cost and which, particularly when the parts exposed to view are constructed of enameled or otherwise suitably and attractively finished metal, is of ornamental appearance and thus suitable for installation in proximity to or association with bathroom fixtures, surgical appliances and the like of the modern standards of beauty and finish.

The invention further includes other objects and novel features of design, construction and arrangement hereinafter more particularly mentioned or which will be apparent from the following description of certain forms of the invention illustrated in the accompanying drawings in which Fig. 1 is a perspective view of one of said forms with the plate occupying its lowered or normal position; Fig. 2 is a similar view with the plate raised to substantially horizontal position, and Figs. 3 and 4 are central vertical transverse sections, respectively, substantially on lines 3—3 and 4—4 in Figs. 1 and 2; Fig. 5 is a view generally corresponding to Fig. 4 but showing a slightly different form of the invention embodying a different form of heating unit; Fig. 6 is a similar view illustrating a still further modified form of the invention employing a substantially similar unit; Fig. 7 is a perspective view of the form of the invention shown in Fig. 6 but with the plate

removed and showing the parts in normal position; Fig. 8 is a similar view showing the same parts in the position which they occupy when the plate is raised; and Fig. 9 is a perspective partially fragmentary view showing the casing in which the heating unit is housed under normal conditions. The same numerals are employed to designate corresponding parts in the several figures.

Referring now more particularly to the form of the invention shown in Figs. 1 to 4 inclusive, the same comprises a plate-like support 1 adapted to be secured in substantially vertical position to a wall or the like; for this purpose the support may be provided with perforated lugs 2 for the reception of screws. Preferably, and as best shown in Figs. 3 and 4, this support may comprise rearwardly extending marginal flanges 1' adapted to abut the wall and thus maintain the central or major portion of the support spaced therefrom so as to provide an air space 3 between it and the wall.

The heating unit or source of heat, generally designated at 5, and hereinafter more fully described, is disposed in a box-like casing 6 located in front of and carried by the support. This casing is preferably formed of sheet metal and comprises a front wall 7, rear wall 8, bottom wall 9 and end walls 10 as well as a pair of laterally spaced, rearwardly extending supporting webs 11, the ends of which may be turned transversely and secured in any suitable way to the face of the support. For supporting the heating unit within the casing a plate 12 may be suitably secured therein in front of and spaced from the wall 8 and the heating unit attached thereto in any convenient way. This unit may be of any suitable form and construction as, for example, a plurality of coils of suitable resistance wire respectively mounted upon vertically spaced cylindrical insulators extending horizontally in the casing, current being supplied to the heating unit through the medium of wires, generally designated as W, extending rearwardly through the rear wall of the casing and through a cylindrical conduit 13 which may be struck up from the support 1 so as to form an integral part thereof.

as shown. The wires may then be carried upwardly in the air space 3 and brought out forwardly through the support for connection to a multipoint switch 16 located on the support preferably near the upper end thereof and by means of which the flow of current through the heating unit can be controlled so as to vary the degree of heat produced thereby; from the switch other wires W' extend to the source of current supply. The particular method and connections employed for controlling the temperature of the heating unit through the medium of the switch 16 or otherwise form no part of the present invention and may therefore be of any form suitable for the purpose, as will be readily understood by those familiar with the art.

Desirably the front wall 7 of the casing 6 is made somewhat shorter than the rear wall 8 and the latter above the heating unit is bent angularly forward so as to correspondingly direct the heated and rising air, while to permit the ingress of air to the casing so it can pass over the heating unit, the rear wall of the casing adjacent its lower extremity may be cut away as at 18; thus, air entering at this point can pass upwardly by convection over the heating unit and thence out of the casing through its upper and open end.

For normally substantially concealing the casing in which the heating unit is disposed, as well as for forming a shelf-like structure when disposed in substantially horizontal position, I provide a hinged element or plate and which is generally designated as 20. This element, which is preferably constructed as an integral unit by forming it up from a single sheet of metal or other material through which heat may be conveyed fairly rapidly from one side to the other, comprises a substantially rectangular central portion 21 and a marginal flange 22 of relatively considerable depth surrounding and extending generally at right angles thereto and is hingedly supported near one edge of its central portion in any suitable way so as to rotate about a horizontal axis, for example by means of a pivot rod 23 extending transversely through the end walls 10 of the casing 6 and projecting laterally therefrom through openings 24 in the flange of the plate, but, if desired, any other suitable means may be utilized for effecting the requisite hinged connection and support for the plate. Thus, when the plate is lowered to substantially vertical or normal position as shown in Figs. 1 and 3 it substantially covers and conceals the casing 6 but when swung upwardly about its hinge connections therewith substantially to the position shown in Figs. 2 and 4, the plate forms a substantially horizontally extending shelf upon which any desired articles may be disposed.

Means are provided for maintaining the

plate in raised or substantially horizontal position, said means preferably comprising a pair of arms 35 respectively pivoted or hinged to lugs 36 on the front face of the support 1 and in turn pivoted as at 37 to the free ends of a generally U-shaped member 38 which is pivoted to the plate on pivots 39 so as to swing vertically. Thus, when the plate is lowered, the arms 35 and member 38 fold up or buckle about pivots 37 to assume the position shown in Fig. 3 but when the plate is raised the arms and member are brought into substantial parallelism and thus form a strut adapted to hold the plate in elevated position as in Fig. 4. To prevent pivots 37 from passing over center, the arms are each provided with a lug 40 which engages member 38 when the parts are in extended position and prevents them from buckling downwardly.

As hitherto stated the cool air enters the casing 6 near the bottom thereof and moves upwardly therein by convection until it finally escapes from the upper end of the casing, after being heated in its passage over the heating unit, and thence passes into the room. To facilitate the escape of this heated air from the interior of the plate when the latter is in lowered or substantially vertical position, that portion of the marginal flange of the plate which under these conditions is uppermost is preferably provided with a series of holes 45 through which the heated air can readily escape and pass into the room. However, when the plate is raised to substantially horizontal position these holes or openings are then disposed adjacent the back of the casing 6 and more or less covered thereby so that very little heated air can escape through them although it can still escape from the top of the casing. Therefore, in order to deflect this air against the under side of the central part of the plate so it will exercise a heating effect thereon, I preferably provide a movable deflector 42 in the form of a sheet of metal of somewhat smaller dimensions than the central portion of the plate so it will readily seat inside of the latter and hinge the same along one edge to the front wall of the casing as at 43 so the deflector is free to swing upwardly and downwardly in correspondence with the movements of the plate, the deflector being desirably of sufficient length to overhang at its free end the central part of the U-shaped member 38 so as to ride on the same. Thus, when the plate is lowered the deflector hangs substantially vertically between the front wall of the casing and the central portion of the plate but as the latter is raised the deflector, through its contact with the member 38, is caused to follow the plate upwardly and ultimately assume a slightly upwardly and forwardly inclined position as best shown in Fig. 4 so that, in effect, a sort of chamber

is formed between the under face of the plate and the deflector into which the heated air rising from the casing 6 is directed by the forwardly inclined upper portion of the rear wall 8 of the casing so that it can exercise its maximum heating effect on the plate.

It will thus be apparent that the heater may be readily employed when the plate is in lowered position for heating the room in which it is disposed, and that under these conditions the cool air entering the casing 6 through the opening 18 is free to rise therein and be progressively heated as it passes over the heating unit from which point it passes out of the casing into the interior of the plate and thence out into the room through the openings 45, the degree of heat being of course under the control of the operator through the medium of the multipoint switch 16 which is ordinarily so designed as to afford at least three degrees of heat regulation for the heating unit. When it is desired to utilize the plate as a shelf, it is merely necessary to lift the same to substantially horizontal position as shown in Fig. 4 upon the attainment of which the arms 35 and member 38 are automatically brought to and locked in extended position and thus operate to hold the plate raised until they are manually slightly buckled upwardly about pivots 37 preparatory to again lowering the plate. It will be further apparent that when the plate is raised the heated air from the casing is directed in major portion against the under surface of the plate so as to heat the latter and, in turn, to heat or dry any article which may be disposed thereon, while at the same time the heated plate exercises a considerable heating effect upon the surrounding atmosphere by radiation, while as the control of the temperature of the heating unit is entirely independent of the position of the plate current may be supplied to the unit when and as desired irrespective of the adjusted position of the plate.

In the form of the invention shown in Fig. 5 another type of heating unit is utilized, namely, an ordinary radiant heater such as is in common use and which comprises a parabolic reflector 50 having a heating element 51 disposed substantially at its center to which current is supplied by a cord or wire W. This element is mounted in a casing 52 open at the front and preferably closed on all four sides and at the back and provided with perforated lugs 53 to enable the heater to be conveniently secured to a wall or other supporting surface. As in the form of the invention heretofore described, the heating unit is preferably mounted within the casing on a plate 54 offset from the back wall of the casing and connected to the latter by flanges or webs 56 so as to provide an air space 55 between the plate and the back wall of the casing, the cord W being led through this space and thence down-

wardly out of the casing for connection to the source of current supply. The casing may be provided with a pair of laterally spaced upwardly projecting ears 57 through which and the flange of the plate are extended pivots 58 upon which the plate can turn in a manner similar to that heretofore described. The heating unit is mounted within the casing in a substantially vertical position so that the heat radiated therefrom is projected outwardly and forwardly, desirably against reflecting plates 59 and 59' respectively extended between the pairs of arms 35 and the arms of member 38 and secured to and movable therewith. Thus when the arms and member are in extended position as shown in Fig. 5, the two plates together form a reflecting surface against which the rays of heat from the heating unit are projected and by which the said rays are directed in a generally upward direction against the under side of the superjacent plate as indicated by the broken lines in the said figure, thereby heating the plate when it is in raised position. The positions assumed by the plate and strut forming members when the plate is lowered are indicated in dotted lines in Fig. 5.

It will be noted that in both of the forms of the invention to which reference has heretofore been made, the heating unit is supported in relatively fixed position with respect to the casing in which it is housed but in the form of the invention now to be described, the heating unit is so arranged as to be relatively movable with respect to the parts from which it derives its support, while the plate as in the case of the said other forms is relatively movable with respect to the unit.

Thus, in the form of the invention shown in Figs. 6 to 9 inclusive, the heating unit, as in the case of the form shown in Fig. 5, comprises a parabolic reflector 60 having a heating element 61 disposed substantially at its center and to which current is supplied through the medium of a cord or wire W. The reflector 60 is provided with a marginal flange 62 which is riveted or otherwise suitably secured at diametrically opposite points to a pair of laterally spaced parallel bars 63 and 64 which are hinged at their upper ends on a horizontally and transversely extending rod 65 so that the bars can swing in a vertical plane. The bars are also connected at their lower ends to a rod 66 about which the ends of the bars are bent, and the ends of the rod in turn are bent upwardly and then outwardly to extend through holes in the U-shaped member 38. Under normal conditions the heating unit may be housed in a sheet metal box-like casing 70 which is closed except at the front and supplied with perforated lugs 71 to facilitate its attachment to a wall. A shield or plate 72 is preferably arranged inside of the casing and spaced from its back wall so as to provide an air space between the heater and

that wall to insure against the latter becoming overheated. The casing also is provided with upwardly projecting ears 74 to which the plate is suitably hinged on pivots 75.

5 It will thus be apparent that as the plate is swung up from lowered to raised position, the heating unit will likewise be moved up though to a somewhat lesser extent so that when the plate is fully raised the heating unit will occupy an angular position with respect thereto as shown in Fig. 6 and in which it is effective to direct the heat rays which it generates directly against the under surface of the plate so as to heat the same. Equally, when the plate is swung downward to normal or substantially vertical position the heating unit will likewise move downward until it is substantially housed in the casing 70 and thus in a position to direct 10 its heat rays against the center of the plate, the major portion of which is closely adjacent the front of the unit and in position to receive the projected rays. Under these conditions the heating effect on the room exerted 15 by the heater is produced both by direct radiation from the plate and also by heated currents of air which travel upwardly in the plate and out of the apertures 45 in its then uppermost flange.

20 30 While I have herein illustrated and described several forms of my invention with considerable particularity I do not thereby desire or intend to limit myself particularly thereto nor to any precise details of construction or arrangement of the various parts as the same may be modified in numerous particulars if desired and various forms of heating units either electric or gas may be employed either with or without means for controlling or regulating the heating effect which they are capable of exerting without departing from the spirit and scope of the invention as defined in the appended claims.

40 Having thus described my invention, I claim and desire to protect by Letters Patent 45 of the United States:

50 1. In a heater, the combination of a source of heat, means for securing said source of heat to a wall, a plate, means for supporting the plate in movable relation to the source of heat to occupy a horizontal position above the source of heat or a vertical position in front of the source of heat.

55 2. In a heater, the combination of a source of heat, means for supporting said source of heat from a wall, a plate, means for supporting the plate in movable relation to the source of heat and operable to permit the plate to be swung from horizontal position 60 above the source of heat to vertical position in front of the source of heat whereby the plate is directly heated from said source when in either of said positions.

65 3. In a heater, the combination of a supporting structure adapted to receive support

from a vertical wall, a source of heat supported from said structure, a plate also supported from said structure and movable relatively to said source of heat to occupy a horizontal position above said source or a vertical 70 position in front of said source.

4. In a heater, the combination of a supporting structure adapted to be secured to a vertical wall, a source of heat supported from said structure, a plate supported from said structure and movable about a horizontal axis adjacent one of its edges from a vertical position in front of said source of heat to a horizontal position above said source, and means for releasably supporting the plate 75 80 in said last mentioned position.

5. In a heater, the combination of a supporting structure adapted to be secured to a vertical wall, a source of heat deriving support from said structure, a flanged plate 85 hingedly supported from the structure and movable about a horizontal axis adjacent one of its edges and relatively to said source of heat from a vertical position in front of said source of a horizontal position above 90 said source, and means for releasably supporting the plate in said last mentioned position.

6. In a heater, the combination of a supporting structure adapted to be secured to a vertical wall, a source of heat deriving support from said structure, a flanged plate 95 hingedly supported from the structure and movable about a horizontal axis adjacent one of its edges and relatively to said source of heat from a vertical position in front of said source to a horizontal position above said source, and means for releasably supporting the plate in said last mentioned position, the flange of said plate being operative to substantially enclose the source of heat when the plate is in vertical position and having a series of apertures in that portion of the flange which is uppermost when the plate is 100 105 in said position.

110 In witness whereof, I have hereunto set my hand this 11th day of April, 1928.

JOHN S. FORBES.
